US0D1073903S

(12) **United States Design Patent** (10) Patent No.: **US D1,073,903 S**
(45) Date of Patent: ** May 6, 2025

(54) **COMBINED AIR PURIFIER WITH VENTILATOR AND STAND**

(71) Applicant: **IQAir AG**, Goldach (CH)

(72) Inventors: **Christoph Zuberbuehler**, Staad (CH); **Florian Buchwalder**, St. Gallen (CH); **Frank Hammes**, Horn (CH)

(73) Assignee: **IQAIR AG**, Goldach (CH)

(**) Term: **15 Years**

(21) Appl. No.: **29/875,432**

(22) Filed: **May 4, 2023**

Related U.S. Application Data

(62) Division of application No. 35/513,890, filed on Sep. 23, 2021 (U.S. filing date under 35 U.S.C. 384), and having an international filing date of Sep. 23, 2021, now Pat. No. Des. 1,031,962.
